UNITED STATES PATENT OFFICE.

MAE S. GELLMAN BURR, OF COMMACK, NEW YORK.

MILK-BOTTLE CAP.

1,170,409.

Specification of Letters Patent.

Patented Feb. 1, 1916.

Application filed June 11, 1915. Serial No. 33,582.

To all whom it may concern:

Be it known that I, MAE S. GELLMAN BURR, a citizen of the United States, residing at Commack, in the county of Suffolk and State of New York, have invented certain new and useful Improvements in Milk-Bottle Caps; and I do hereby declare the following to be a full, clear, and exact description of the invention, such as will enable others skilled in the art to which it appertains to make and use the same.

This invention is an improved milk bottle cap, the object of the invention being to provide an improved cap of this kind which is entirely sanitary, serves to protect the mouth of the bottle both inside and outside against the entrance of germs, dust and the like and which also enables the mouth of the bottle to be made without the usual groove and shoulder on the inside, required by the caps heretofore commonly in use, which groove and shoulder prevent the bottle mouth from being easily cleaned.

The invention consists in a bottle cap having an exterior flange to fit around the mouth and also having an interior flange or collar to fit in the mouth of the bottle so that the bottle mouth is protected both on the outside and on the inside, as hereinafter more fully described and claimed.

In the accompanying drawings:—Figure 1 is a vertical sectional view of a portion of a milk bottle having a mouth constructed in accordance with my invention and provided with a sanitary cap also constructed in accordance with my invention. Fig. 2 is an inverted plan, partly in section, of the cap. Fig. 3 is an elevation, with the central portion broken away, of the blank from which the collar or inner flange is formed.

The milk bottle 1 for use in connection with my improved cap 2 has a plain mouth 3 presenting smooth inner and outer surfaces 4—5, which are entirely unobstructed, the usual groove and shoulder on the inner side of the mouth being omitted, and this being highly desirable as such groove and shoulder render it difficult to thoroughly clean the bottle as the said shoulder forms a lodgment for dust, dirt and other impurities.

My improved cap may be made of paraffined paper or other suitable material, and

is provided with an outer flange 6, annular in shape, and which fits around the outer side of the bottle mouth. The cap is also provided with an inner flange or collar 7 to closely fit in the bottle mouth and against its inner surface 5, this inner flange or collar being deeper than the outer flange as shown in Fig. 1.

Within the scope of my invention the inner flange or collar may be formed either integrally with or separately from the cap. It is here shown as formed separately from the cap and as being formed from a blank strip 8 of suitable length and width, having a tongue 9 at one end and a slot 10 near the other end to receive the tongue and thereby secure the ends of the blank together and in overlapped relation, the blank strip being also provided at its outer edge, at suitable points, with tongues 11 which are passed through slits 12 in the cap and are bent inwardly on the outer side of the cap as shown in Fig. 1 and as indicated in dotted lines in Fig. 2.

Having thus described my invention, I claim:—

A bottle cap of the class described having an outer flange wall to fit around the exterior of the bottle mouth and having a pair of spaced slits in the top thereof, and also having an inner wall or collar having a pair of ears formed on its longitudinal edges at spaced distances apart, said ears adapted to fit up into the slots in the cap for securely holding the inner flange integral to the cap and at spaced distance away from the outer flange wall of the cap, said inner flange or collar being adapted to engage the inner face of the bottle mouth and provided on one of its vertical ends with a locking tongue intermediate of its longitudinal edges and having a vertical slot formed adjacent its opposite end intermediate the longitudinal edges thereof, said tongue adapted to fit in said slot for securely holding the inner flange against the interior of the bottle mouth.

In testimony whereof I affix my signature in presence of two witnesses.

MAE S. GELLMAN BURR.
